OXYGEN PROCESS

Henry J. Ogorzaly, Summit, N. J., assignor to
 Standard Oil Development Company, a corpora-
 tion of Delaware

Application October 12, 1946, Serial No. 703,000

8 Claims. (Cl. 62—175.5)

1

The present invention is concerned with an improved process for the production of oxygen from air. The invention is more particularly concerned with an arrangement and sequence of heat exchanging stages by which improved efficiency in the exchange of heat is secured. In accordance with the present process at least one solid heat exchange medium is circulated between the incoming feed air stream and the outgoing product stream under conditions to secure direct contact between the circulating heat exchange medium and the air stream and the product stream. The preferred modification of the present invention comprises employing a plurality of heat exchange mediums, one of which comprises solid materials, for transferring refrigeration from the product stream to the feed air stream and simultaneously controlling the critical temperature range over which the particular selected medium is used.

By operating in accordance with the present invention unexpected desirable results are secured and the efficiency of the operation is materially improved.

It is well known in the art to manufacture oxygen and nitrogen from air. In these processes, the air is liquefied and fractionated to secure products having the desired high quality and purity. Since the operation is conducted at very low temperatures, it is obvious that one major problem encountered is the efficient transfer of refrigeration from one stream to the other. Various proposals and suggestions have been made for the efficient transfer of heat from the incoming air stream to the chilled outgoing product streams. In the design of suitable heat exchange equipment, the problem is complicated by the fact that in cooling air to the desired temperature, water vapor freezes out in the form of ice, and carbon dioxide in the form of carbon dioxide snow. Thus, in a relatively short period of time the heat exchange equipment is plugged due to the ice and carbon dioxide snow.

One process that is currently used to overcome the plugging of exchangers or accumulators is to use reversible exchangers or accumulators. In this process the incoming air stream is compressed to a pressure in the range from about 4 to about 8 atmospheres and higher and is caused to exchange heat countercurrently against the outgoing cold product streams. The cold product streams are usually at lower pressures, generally around atmospheric pressure. After the streams have flowed through their respective channels for a period of time, and the ice and

2

snow plugging in the air channel has not as yet reached a critical maximum, the flow paths of the respective streams are switched. That is, the cold product streams are caused to flow through the paths previously employed by the warm incoming air, while the air employs the passageways previously used by the product gases. The direction of flow of the gaseous streams is not changed. As a result of this "reversal," the carbon dioxide and the water vapor deposited from the air in the previous half cycle are caused to revaporize or sublimate into the lower pressure product streams and they are then carried out with the product gases.

15 Since the outgoing nitrogen and oxygen product streams are colder than the chilled air stream from which the ice and carbon dioxide is condensed, the success of the reversible exchanger depends upon a balance of the differences in 20 the respective temperatures and pressures. If carbon dioxide snow is to be revaporized there exists a critical maximum temperature difference which must not be exceeded, otherwise sublimation of the carbon dioxide snow will not be secured even at the lower pressure of the reversing streams.

I have now discovered an improved process for transferring refrigeration from the chilled product streams to the incoming feed air streams. 30 In accordance with my invention, I utilize at least one solid heat transfer medium to transfer refrigeration between the respective streams in an efficient manner. The process of my invention may be readily understood by reference to 35 the attached drawing illustrating an adaptation of the same.

The incoming feed air stream is introduced into the system by means of line 1. The feed air stream is introduced into centrifugal compressors P—1 or equivalent means. Compressors P—1 may include intercoolers and are preferably driven by a condensing steam turbine. The feed air stream is compressed to 5 atmospheres gauge, withdrawn from compressors P—1 by 45 means of line 2 and passed to after-cooler E—1 in which the air stream is cooled to a temperature of about 100° F. Water is introduced into after-cooler E—1 by means of line 3 and withdrawn by means of line 4. The compressed air is introduced into the top of water removing zone 6 by 50 means of line 5. The condensed water is removed in zone 6 and collects in the bottom thereof. A portion of the condensed water is withdrawn by means of line 7 and used as make-up water in the circulating brine solution hereinafter de-

scribed. Any remaining or excess water is removed from the system by means of line 8. The compressed air is removed overhead from zone 6 by means of line 9 and introduced into the bottom of air-brine contacting zone T-1 through a distributing head or manifold 10. The air flows upwardly through zone T-1 and is cooled to a temperature of about -10° F. by downflowing calcium chloride brine which is introduced into the upper part of zone T-1 by means of line 11. The brine is introduced at a temperature of about -17° F. and withdrawn by means of line 12 at a temperature of about 98° F.

Air brine contacting zone T-1 may comprise any suitable type of equipment. Zone T-1 may contain wooden grids G-1, G-2, G-3 and G-4 or equivalent means as packing to secure efficient contact between the counterflowing streams. Zone T-1 may likewise contain adequate distributing troughs and the like.

The air stream cooled at a temperature of -10° F. is drawn overhead from zone T-1 by means of line 13 and introduced into ammonia chilling zones E-2a and E-2b by means of lines 14 and 15 respectively. The ammonia chilling zones or equivalent means are designed to cool the air at a pressure of 5 atmospheres (gauge) from about -10° F. to about -30° F. The air is maintained on the tube side while the ammonia is maintained on the shell side of the exchanger. The air in the tube side is periodically replaced with nitrogen gas in order to remove ice which condenses out from the air on the tube side and avoid plugging of the tubes.

Ammonia liquid is introduced into zones E-2a and E-2b by means of lines 16 and 17 respectively. The ammonia boils at about -40° F. at a pressure of 10.4 pounds per square inch absolute on the shell side and is removed from zones E-2a and E-2b by means of lines 18 and 19 respectively.

Air at a temperature of about -10° F. is introduced into zone E-2a by means of line 14 and withdrawn from zone E-2a by means of line 20 at a temperature of -30° F. During this cycle nitrogen is introduced into the tube side of exchanger E-2b at a temperature of about -32° F. by means of line 21. The nitrogen is withdrawn from exchanger E-2b by means of line 22 at a temperature of -33° F. and introduced into the bottom of nitrogen brine contacting zone T-2 hereinafter described.

On the other half of the cycle, air is introduced into zone E-2b by means of lines 13 and 15 and withdrawn from zone E-2b by means of line 23. During this cycle nitrogen is introduced into the tube side of zone E-2a by means of line 24, withdrawn by means of line 25 and likewise introduced into the bottom of zone T-2.

Zones E-2a and E-2b with their accompanying feed and withdrawal lines for ammonia, nitrogen and air, are properly equipped with a suitable valve arrangement so that the above described cycle may be secured. It is to be understood that it is within the scope of my process to operate zones E-2a and E-2b in parallel for at least a portion of the time and only to pass nitrogen through the tubes for a sufficient length of time to keep the tubes from plugging.

In accordance with my invention, the air withdrawn from zones E-2a and E-2b is introduced into the bottom of an air-solid contacting zone T-4. For the purpose of illustration, in accordance with a preferred modification of my invention, the solids comprise lead pellets. It is

to be understood that other solids, as for example metallic silver, calcium, zinc or salts such as silver iodide, may be employed. In general, the use of solids other than lead will require more than one stage of direct contact between the solid and the gases to effect the transfer of heat over the same range of temperature. The air is introduced into the bottom of zone T-4 by means of distributing lines 26. The air flows upwardly through the interstices of a bed of downward flowing lead pellets 27. Air at a temperature of about -275° F. is withdrawn from the top of zone T-4 by means of line 28. Air lead contacting zone T-4 is operated at a pressure of about 73 pounds per square inch gauge pressure. The lead pellets are introduced at a temperature of about -285° F. and are withdrawn at a temperature of about -31½° F. Although the depth of the bed may vary, it is preferred for example, that when the cross-sectional area of zone T-4 is about 226 square feet and the equivalent diameter about 17 feet with the height of the sides around 13 feet, the depth of the lead pellet bed should be about 8 feet.

The chilled air at a temperature of about -275° F. is introduced into the bottom of high pressure fractionating tower T-8. This tower is operated at a pressure of about 72 pounds per square inch gauge and between the temperature limits of from about -280° F. to -287° F. This high pressure tower comprises suitable fractionating plates. Substantially pure nitrogen is removed as an overhead vapor stream from the high pressure tower by means of line 29 at a temperature of about -286.5° F. while the bottoms stream comprising an oxygen-rich liquid stream containing from about 40% to about 50% of oxygen is removed by means of line 30 at a temperature of about -280° F. From the bottom of high pressure fractionating zone T-8, I withdraw a slurry comprising solid carbon dioxide by means of line 31 at a temperature of about -280° F. This slurry is circulated by means of centrifugal pump P-2 through carbon dioxide filter zone V-2 in which the solidified carbon dioxide is removed. The bottoms slurry stream from which carbon dioxide is removed is introduced into line 30 by means of line 32 and handled as herein-after described. A portion of the slurry recirculated by pump P-2 is not passed through filter zone V-2, but is introduced into the top of a scrubbing section of high pressure fractionating tower T-8 by means of line 33. This portion of the slurry counter-currently contacts the upflowing air stream introduced into the bottom of zone T-8 and removes therefrom carbon dioxide snow and other solids. Carbon dioxide filter zone V-2 may be equipped to be blown through with cold compressed air and to flush out the carbon dioxide deposit with a purge stream of nitrogen at intervals.

The oxygen-nitrogen stream comprising about 45% oxygen and 55% nitrogen at a pressure of about 70 pounds per square inch is passed to a high pressure tower bottoms cooler zone E-3. In exchanging zone E-3 the liquid oxygen-nitrogen stream is cooled from a temperature of about -280° F. to a temperature of about -289° F. This cooled oxygen-nitrogen stream is withdrawn from zone E-3 by means of line 34 and introduced into an intermediate point of low pressure fractionating tower T-9. Liquid nitrogen at a temperature of about -306° F. is introduced into zone E-3 by means of line 35 and withdrawn

from zone E-3 at a temperature of about -284° F. by means of line 38.

The liquid feed stream introduced into zone T-9 by means of line 34 flows downwardly in the low pressure tower through the stripping section in which it is freed of nitrogen by contact with vapors rising from the reboiler section in the bottom of the tower. The nitrogen-free liquid stream is vaporized in the reboiler section and a part of the vapor is returned up the tower while another part is withdrawn as oxygen product from low pressure tower T-9 by means of line 38 at a temperature of -292° F. The heat supplied to the bottom of low pressure tower T-9 is maintained by condensing the major part of the nitrogen leaving the high pressure tower T-8 through line 29. A part of the condensed nitrogen is returned by means of line 39 to provide reflux in high pressure tower T-8 while another part is introduced into the top of low pressure tower T-9 by means of line 41 through throttling valve 40. Prior to introducing this reflux nitrogen into the top of low pressure tower T-9 it is passed through a reflux nitrogen cooler E-4. In this zone liquefied nitrogen is cooled at 70 pounds per square inch from its boiling point of -286.5° F. to -300° F. with vapor nitrogen at about 3 pounds per square inch gauge pressure and at a temperature of -315° F. to about -306° F. The vapor nitrogen is introduced into zone E-4 by means of line 42 and withdrawn by means of line 35. Low pressure tower T-9 is operated at a pressure of about 3.5 pounds per square inch under conditions to withdraw overhead by means of line 37 a pure vaporous nitrogen stream at about -315° F.

A portion of the nitrogen stream removed overhead from high pressure tower T-8 by means of line 29, the major part of which is passed to the condenser-reboiler in the bottom of zone T-9, flows to nitrogen expander surge drum V-3 by means of lines 43 and 44. Prior to introducing this stream into zone V-3, it is mixed with a small stream of nitrogen at a temperature of about -35° F. which is introduced by means of line 45. The relative quantities employed are sufficient to secure a temperature of at least -256° F. at a pressure of 72 pounds per square inch in the lower half of zone V-3.

The warmed nitrogen stream is withdrawn from the lower half of zone V-3 by means of line 46 at a temperature of at least -256° F. and at a pressure of about 72 pounds per square inch gauge, passed to centrifugal expansion engine P-3 and then discharged into the upper half of zone V-3 at a temperature of about -315° F. and at a pressure of about 5 pounds per square inch by means of line 47. The cool vapors are withdrawn from the top of zone V-3 by means of line 42 and handled as hereinbefore described. A sufficient quantity of nitrogen withdrawn from the top of zone T-8 by means of line 29 is passed through expander nitrogen-lead contacting zone T-7, in order to warm it from about -286.5° F. to about -35° F. This is accomplished by means of lines 45 and 48.

The lead pellets are withdrawn from air-lead contacting zone T-4 by means of line 50 at a temperature of about -31½° F. and under pressure of about 72 pounds per square inch gauge. These lead pellets comprise pellets having a diameter of approximately $\frac{1}{4}$ ". These pellets are moved under pressure through bucket conveyor arrangement 50 or similar means and various portions of them passed into lead pellets

75

accumulator zones V-4, V-5 and V-6. Lead accumulator zone V-4 is an accumulator zone for the nitrogen tower, while lead accumulator zone V-5 is a lead accumulator for the oxygen tower, and lead accumulator zone V-6 is a warm lead accumulator for the expander nitrogen tower.

The lead pellets from the lead accumulator zone V-4 are passed into the lock hopper feed zone for the nitrogen tower V-7. In zone V-7 the pressure on the pellets is reduced from about 72 pounds per square inch gauge to the low pressure of about 2 pounds per square inch gauge at which nitrogen-lead contacting zone T-5 operates. These lead pellets are passed through a suitable valve arrangement from zone V-7 into the product nitrogen-lead contacting zone T-5. In this zone the lead pellets form a bed 51 in the bottom area thereof. Product nitrogen is withdrawn from zone E-3 by means of line 36 is introduced into zone T-5 by means of distributing lines 52. This product nitrogen flows upwardly between the interstices of the lead pellets of bed 51 and is withdrawn from the upper part of zone T-5 by means of line 21.

The product nitrogen flows through zones E-2a and E-2b as previously described, and is then introduced into nitrogen brine contactor T-2 by means of line 53. A portion of the nitrogen may by-pass zones E-2a and E-2b by means of line 54. The product nitrogen flows upwardly through zone T-2 and countercurrently contacts downflowing brine which is introduced into the upper part of zone T-2 by means of line 12. The product nitrogen is vented overhead from zone T-2 into the atmosphere, or it may be collected and used in any manner desirable. Nitrogen brine contacting zone T-2 may contain any suitable packing or distributing means.

The lead pellets are withdrawn from zone T-5 by line or conveying means 55 and introduced into lock hopper feeding zone V-10. In this zone the pressure by proper control of the respective valves is increased from the pressure existing in zone T-5 of about 2 pounds gauge to the pressure existing in zone T-4 of about 73 pounds per square inch.

The lead pellets introduced into zone V-5 which comprises the lead accumulator zone for the oxygen tower are then passed into zone V-8 which comprises the lock hopper feeding into low pressure product oxygen-lead contacting zone T-6. The lead pellets form a bed 60 in the lower area of zone T-6. Product oxygen withdrawn from low pressure fractionating zone T-9 by means of line 38 is introduced into zone T-6 by means of distributor lines 61. The product oxygen flows upwardly through bed 60 and is withdrawn from the upper area by means of line 62.

This product oxygen is then passed into the lower section of oxygen brine contacting zone T-3. The product oxygen flows upwardly through zone T-3 and countercurrently makes heat exchange with the down-flowing brine which is introduced into the top of zone T-3 by means of line 63. Product oxygen is removed overhead from zone T-3 by means of line 54 and handled in any manner desirable. Lead pellets are removed from zone T-6 by means of conduit or conveying means 64 and handled in a manner similar to that described with respect to the pellets by means of line 55.

Lead pellets passed into zone V-6 are passed

into cold lead accumulator zone T-7 which operates under pressure of about 72 pounds per square inch gauge. In this zone the lead pellets contact, as heretofore described, nitrogen which is introduced into zone V-9 by means of line 48 and withdrawn by means of line 45. The lead pellets are withdrawn from zone T-7 and introduced into cold lead accumulator V-9 which acts as a feed hopper to zone T-4. The lead pellets are passed from zone V-9 to zone T-4 by means of line 70 and handled as heretofore described.

My invention is generally concerned with an improved oxygen product process wherein oxygen is separated from air by a liquefaction-fractionation process in which a major part of the heat transferred from cold product gases to relatively warmer entering air is effected by means of a circulation of solid lead particles. In general, the process comprises compressing air to 5 atmospheres gauge and cooling to about 100° with water. The air is then cooled with a 30% calcium chloride brine solution or an equivalent solution in a tower preferably packed with vertical wood grids in order to cool the temperature to about -10° F. In a second air cooling stage, the air is further chilled with ammonia or an equivalent cooling medium to about -30° F. The air is withdrawn from the second cooling stage and in accordance with my process is passed through a bed in which the heat is transferred from the outgoing product streams to the incoming air stream in the tertiary cooling stage by means of a solid cooling transfer medium. The preferred method of operating is to employ a moving bed of solid heat transfer medium which comprises metallic spheres, as for example lead spheres. The diameter of the spheres may vary in the range from about $\frac{1}{8}$ " to 1" and higher. It is preferred that the diameter of the spheres be in the range from about $\frac{1}{4}$ " to $\frac{3}{4}$ " in diameter.

In the tertiary cooling stage, the air is chilled to a temperature of about -275° F. The chilled air which is close to a saturation point is introduced into the bottom of a high pressure fractionating tower operating at a few pounds below 5 atmospheres gauge where it is first subjected to a scrubbing action with a pump-around slurry stream for the purpose of removing carbon dioxide snow carried in the gas. A portion of the slurry is passed through a sand filter or equivalent means, preferably provided in duplicate from which the carbon dioxide is periodically vaporized in amounts equivalent to the rate of introduction in the air feed.

The air fractionating system comprises a low pressure tower operating at a few pounds per square inch above atmospheric pressure and a high pressure tower which operates as described heretofore.

Additional refrigeration is obtained by the expansion in a work engine of approximately 13% of the nitrogen product, which is available as gaseous vent from the high pressure tower. The cold returning products leaving the fractionation system in gaseous form are used first to chill the $\frac{1}{4}$ " lead pellets to -285° F. before these pellets are employed to cool the incoming air. A small side stream flow of lead is also employed to warm the portion of the nitrogen entering the expansion engine, in order to avoid condensation within the engine. The separated products leave the lead contacting towers at -32° F. and are used to chill the circulating brine solution prior to its contact with the warm compressed air. The contact of

the brine with these low pressure gases results in a net vaporization loss of water which is balanced by introducing a portion of the water in the compressed air.

5 By far the major part of the water in the entering air stream is removed in the compressor after-cooler and the brine contact tower. A residual is deposited in the ammonia chillers. These are accordingly provided in duplicate with nitrogen gas at low pressure returning through the tubes of the unit not employed in chilling air. The deposited ice is thus sublimated into the low pressure returning stream. Automatic switching of the flows at intervals is provided. A remaining 10 small proportion of water is carried further into the lead circulation system and is transferred by the lead from its point of deposition in the air tower to the product towers where it is vaporized.

15 The CO₂ content of the air is substantially all 20 deposited as a solid in the lead contacting tower. Since the temperature at the bottom of this tower is too high to permit the retention of CO₂ solid on the spheres leaving the tower, the upper portion of the tower fills with CO₂ snow. This is 25 sufficiently dry in nature so that it is carried overhead in the chilled gas, to be removed in the slurry scrubbing system and sand filter provided in the fractionation section.

30 In a designed system, the lead circulation system requires the transfer of approximately 43 35 tons per minute of lead to a vertical height of 150 feet and its separation into two major and one small stream. Because of the pressure differentials existing between the air and product streams, 40 lock hoppers are provided to effect pressure seals between these streams. Automatically operated 45 valves in this cycle operate at a one minute interval between changes in position.

50 The essential novelty of this process resides in 55 the storage of refrigeration in the circulating solid and its bodily transport within the solid to a zone where it can be utilized. Metallic lead is the most satisfactory solid, but other materials which may be used for a solid heat transfer

45 medium comprise tellurium, silver, calcium, zinc, potassium bromide, silver iodide and the like. Except for its rarity, tellurium is equally as satisfactory as lead for use in air separation plants. All other solids, however, are less satisfactory in 50 that their heat capacity varies to a greater extent with change in temperature level in the refrigerating zone. In adiabatic interchange of heat between solids and cold gases, which maintain substantially constant heat capacity, appreciable 55 temperature separation between the solid and the gas occurs as a consequence of the variation in heat capacity of the solid at different temperature levels. When the solid is utilized for transferring heat between two gases, a differential 60 temperature separation from either gas in excess of the total differential between the two gases cannot be tolerated. As a result, a single-stage 65 of gas-solid contacting can only be used to transfer heat between two gases over a limited range of temperature which is defined by the variation in heat capacity of the solid with temperature level and by the magnitude of the temperature differential between the two gases. The allowable range of temperature is greatest with lead among 70 common metals, followed by silver, calcium, and zinc. Silver iodide and potassium bromide are among the better salts. In many applications of heat transfer by direct countercurrent contact of gas with moving solid, this factor is of minor 75 importance; but when the differential tempera-

ture between the two gases being exchanged is small, as in air separation, it becomes of paramount importance. If a solid is employed whose heat capacity varies with temperature in excess of tolerable limits for a single-stage operation, one or more additional stages of contacting must be introduced in order to reduce the temperature range to within the limits established by the characteristics of the solid employed.

The process of my invention is not to be limited by any theory as to mode of operation, but only in and by the following claims in which it is desired to claim all novelty insofar as the prior art permits.

I claim:

1. In a process for the manufacture of nitrogen and oxygen gas from air and wherein liquid air is fractionated to produce a cold oxygen and a cold nitrogen stream, the improvement which comprises employing 3 successive cooling stages for an incoming air stream to be fractionated, cooling the previously cooled incoming air stream in the third and coldest zone by directly contacting the chilled gaseous product streams in a countercurrent manner with a moving solid transfer medium, whereby said solid transfer medium is chilled and said product streams are warmed, then contacting the said previously cooled incoming air stream with said chilled moving solid heat transfer medium moving countercurrently, the said previously cooled incoming air stream and to warm the solid heat transfer medium and recycling said warm solid heat transfer medium to said product streams.

2. Process as defined by claim 1 wherein said solid medium comprises metallic spheres having a diameter in the range from about $\frac{1}{4}$ " to about $\frac{3}{4}$ ".

3. Process as defined by claim 1 wherein said solid medium comprises lead spheres.

4. In a process for the manufacture of nitrogen and oxygen gas from air and wherein liquid air is fractionated to produce a cold oxygen and cold nitrogen stream the improvement which comprises, cooling the air from a temperature in the range from about 90° F. to 110° F. to a temperature in the range from about -5° F. to -15° F. by circulating in direct heat exchange therewith a calcium chloride brine solution, which solution is also circulated in direct heat exchange with the nitrogen and oxygen products streams, passing the chilled air to a second cooling stage wherein the air is cooled in temperature from about -5° F. to -15° F. to a temperature in the range from about -25° F. to -35° F. by being in indirect heat exchange with a refrigerant medium, passing the chilled air to a tertiary stage wherein the air is cooled from about -25° F. to about -35° F. to a temperature in the range of about -272° F. to -275° F. by being in direct heat exchange with a solid heat exchange medium, said solid heat exchange medium

being circulated and in direct contact with the nitrogen and oxygen product streams.

5. Process as defined by claim 4 wherein said solid medium comprises metallic spheres.

6. Process as defined by claim 4 wherein said solid medium comprises lead spheres having a diameter in the range from about $\frac{1}{4}$ " to about $\frac{3}{4}$ ".

7. In the process for the manufacture of nitrogen and oxygen gas from air wherein air is liquefied and thereafter fractionated to separately obtain oxygen and nitrogen, the improvement which comprises subjecting air to a preliminary cooling by heat exchange with a cold brine solution,

15 cooling the said brine solution by heat exchange with cold gaseous streams of nitrogen and oxygen, respectively, charging the thus cooled air to a second cooling stage where it is further cooled by heat exchange with a refrigerant, withdrawing the thus further cooled air from the said second stage, charging it to a third stage where it is cooled to a temperature as low as about -275° F. by contacting it with a solid heat transfer medium and cooling the said solid heat exchange

25 medium by direct contact with the nitrogen and oxygen streams proceeding from the fractionation prior to contacting the air in the said third stage.

8. The method of producing oxygen by the 30 liquefaction and rectification of air, which comprises passing downwardly through one zone a mass of pellets, flowing upwardly through said zone in contact with said pellets and substantially uniformly distributed therethroughout a

35 stream of rectification product, withdrawing said pellets from the base of said zone at a temperature close to that of the incoming rectification product stream, passing the withdrawn chilled pellets downwardly through a second zone countercurrent to a rising stream of air substantially uniformly distributed throughout the pellets

40 flowing through said second zone, withdrawing the air from said second zone at a temperature close to that of the incoming pellets and withdrawing the pellets from said second zone and reintroducing them into the top of said first mentioned zone.
